HOLDER FOR LIPSTICKS AND THE LIKE

Howard F. Reichenbach, Waterbury, Conn., assignor to Chase Brass & Copper Co. Incorporated, Waterbury, Conn., a corporation

Application February 28, 1941, Serial No. 381,037

3 Claims. (Cl. 206—56)

The present invention relates to improvements in holders for lipsticks and the like, and relates more particularly to holders of the general character referred to which are adjustable for the purpose of shifting the contents of the holder as may be required by the user.

One of the objects of the present invention is to provide a superior adjustable holder for lipsticks and the like which combines simplicity of construction with reliability of operation.

Another object of the present invention is to provide a superior holder of the character referred to in which the actuating-pin or its equivalent which serves to shift the carrier-member, is provided with such full and adequate bearing-connection with the actuating-sleeve that the employment of either complex or costly constructions is not required.

A further object of the present invention is to provide a superior adjustable holder for lipsticks and the like in which a relatively-thin actuating-sleeve may be employed without endangering the reliable operativeness of the device.

With the above and other objects in view, as will appear to those skilled in the art from the present disclosure, this invention includes all features in the said disclosure which are novel over the prior art and which are not claimed in any separate application.

In the accompanying drawing, in which certain modes of carrying out the present invention are shown for illustrative purposes:

Fig. 1 is a view in side elevation of an adjustable holder for lipsticks and the like embodying the present invention;

Fig. 2 is a view thereof in central-longitudinal section taken on the line 2—2 of Fig. 1, but on a larger scale;

Fig. 3 is a transverse sectional view taken on the line 3—3 of Fig. 2;

Fig. 4 is a similar view taken on the line 4—4 of Fig. 2;

Fig. 5 is a transverse sectional view taken on the line 5—5 of Fig. 2;

Fig. 6 is a perspective view of the body-member, detached;

Fig. 7 is a similar view of the actuating-sleeve;

Fig. 8 is a perspective view partly in section of the shell-member; and

Fig. 9 is a perspective view of another form of actuating-pin which may be employed.

The adjustable holder herein chosen for the purposes of illustrating the present invention comprises, in the main, a cup-shaped carrier 10, a substantially-cup-shaped body-member 11, a

longitudinally-split actuating-sleeve 12, a tubular shell-member 13, an inverted cup-shaped cap 14, and a finishing-band 15. All of the said parts may be conveniently formed of sheet metal.

- 5 The cup-shaped carrier 10 above referred to is mounted with freedom for vertical reciprocating movement in the interior of the body-member 11 and carries a mass of lipstick material 16 or such other material as may be desired.
- 10 Slightly above midway of its length, the said carrier 10 is formed with an annular inwardly-projecting bead or rib 17 serving to aid in retaining the material 16 in the carrier 10. Adjacent its lower end, the side wall of the cup-shaped carrier 10 is formed with a radial perforation 18 which receives with a tight frictional grip, the inner shouldered portion 19 of an actuating-member in the form of an actuating-pin generally designated by the reference character 20.
- 15 The actuating-pin 20 above referred to includes a stem 21 smaller in diameter than the shouldered portion 19 thereof and extending into the mass of material 16, as is shown particularly well in Figs. 2 and 4. Outwardly of the shouldered portion 19, the said actuating-pin 20 is formed with a second or outer shouldered portion 22 projecting through a vertical-longitudinal guide-slot 23 formed in the wall of the body-member 11, as is shown particularly well in Figs. 2 and 6.
- 20 The shouldered portion 22 of the actuating-pin 20 also extends outwardly through a helically-inclined actuating-slot 24 in the actuating-sleeve 12 before referred to. If desired, and as shown in Figs. 2 and 4, the actuating-pin 20 may be 25 formed at its outer end with a head 25 of sufficient size to preclude its passage through either the actuating-slot 24 in the actuating-sleeve 12 or the guide-slot 23 in the body-member 11.
- 25 The vertical guide-slot 23 in the body-member 11 intersects the upper edge of the said body-member and extends upwardly from a point closely adjacent an operating-head 26 forming an integral enlarged lower end for the said body-member 11. As thus proportioned, the upper 30 surface of the said head 26 adjacent its junction with the body-member proper, provides an upwardly-facing shoulder 27 adapted to be engaged by the lower end of the actuating-sleeve 12, as well as by other parts of the structure as will 35 hereinafter appear.
- 35 The body-member 11 is proportioned so that its upper end, the body-member 11 is spun or otherwise shaped to provide a downwardly-facing annular coupling-shoulder 28 which is adapted to be engaged by the upper edge 40 of the actuating-sleeve 12 to normally prevent

the undue upward movement of the said actuating-sleeve with respect to the body-member 11.

The actuating-sleeve 12 above referred to is preferably rolled up from a substantially-rectangular blank of sheet metal, and on such a curvature as to require its contraction from its normal untensioned condition shown in Fig. 7, to enable it to fit within the shell-member 13 before referred to. Thus, when installed within the shell-member 13, the parallel opposed edges 29—29 of the said actuating-sleeve are brought into relatively-close proximity as compared to their relative locations as illustrated in Fig. 7. Immediately adjacent its opposed edges 29—29 and at its lower or inner end, the actuating-sleeve 12 is cut away to provide downwardly-facing coupling-shoulders 30—30 for the purposes as will presently appear.

At its upper end the shell-member 13 is shaped to provide an inwardly-set sleeve-supporting portion 31 which is cylindrically-contoured and has its upper end provided with an inturned flange 32. The said sleeve-supporting portion 31 has an interior diameter of such dimensions as to be frictionally engaged with the upper portion of the actuating-sleeve 12 and to enable it to accommodate the said upper portion between itself and the upper portion of the body-member 11, which body-member is free, however, to turn freely with respect to the said actuating-sleeve.

Adjacent its lower end, the shell-member 13 is also formed with a sleeve-supporting portion 33 having an internal diameter corresponding to the internal diameter of the portion 31 above referred to, and like the same is frictionally engaged by the adjacent outer surfaces of the actuating-sleeve 12 under the inherent expanding tension of the latter. A portion of the lower sleeve-supporting portion 33 is slit and set inwardly to provide a coupling-finger 34 having its upper surface positioned for engagement with the retaining-shoulders 30—30 of the actuating-sleeve 12, for purposes as will hereinafter appear.

The portion of the shell-member 13 intermediate its upper sleeve-supporting portion 31 and its lower sleeve-supporting portion 33 is larger in internal diameter than the respective internal diameters of the said portions 31 and 33, so that there is formed interiorly of the said shell-member an annular accommodation-channel 35 in which is accommodated the outer portion of the actuating-pin or member 20 with freedom for the travel of the latter both vertically and transversely in the said channel.

The shell-member 13 is prevented from undue downward movement with respect to the body-member 11 by the engagement of its lower end with the shoulder 27 on the operating-head 26 of the said body-member. Conversely, the said shell-member 13 is prevented from undue upward movement with respect to the body-member 11 by the engagement of its coupling-finger 34 with the coupling-shoulders 30—30 of the actuating-sleeve 12.

The finishing-band 15 before referred to has its lower end resting upon the shoulder 27 of the operating-head 26 of the body-member 11, and is preferably applied with a force fit over the lower portion of the shell-member 13 in order to be fixedly retained thereon and to conceal the coupling-finger 34 and the annular groove resulting from the formation of the lower sleeve-supporting portion 33 of the said shell-member.

Normally the lower edge of the inverted cup-shaped cap 14 rests upon the upper edge of the

finishing-band 15. For the purpose of yieldingly retaining the cap 14 in place upon the shell-member 13, the said shell-member is formed immediately below its upper sleeve-supporting portion 31 with an integral resilient retaining-finger 36 which is preferably pre-set to normally project slightly outwardly and downwardly in the manner shown in Fig. 8. When the cap 14 is applied over the shell-member 13, the retaining-finger 36 just referred to, will yield inwardly and in the event that it possesses any inwardly-projecting irregularities, such irregularities may be conveniently accommodated in the annular accommodation-channel 35 in the shell-member 13, without being jammed against the actuating-sleeve 12 or projected into the path of the outer portion of the actuating-pin 20.

Instead of employing an actuating-member or pin such as 28, an actuating-pin or member such as is generally designated by the reference character 37 and shown in Fig. 9, may be employed. The actuating-pin just referred to comprises a relatively-slender shank 38 which may be tightly fitted into the aperture or perforation 18 in the carrier 10. At its outer end, the said actuating-pin 37 is provided with a relatively-long bearing-portion 39 of cylindrically-contoured form which has a length preferably several times the thickness of the material from which the actuating-sleeve 12 is made. The length of the said bearing-portion 39 is such as to extend through and bear in the inclined helical slot 24 or its equivalent and have its projecting-portion accommodated in the accommodation-channel 35 in the shell-member 13.

In the use of the holder herein shown, the cap 14 may first be removed, whereupon the user may grasp the holder by the periphery of the shell-member 13 or the finishing-band 15, and the body-member 11 may be rotated by means of its operating-head 26 to thereby bodily turn the actuating-pin 20 and the carrier 10. This turning action is effected by one or the other walls of the guide-slot 23 in the body-member 11, which slot serves to limit the actuating-pin 20 and the carrier 10 to relative axial movement with respect to the said body-member. Owing to the frictional inter-engagement of the actuating-sleeve 12 and sleeve-supporting portions 31 and 33 of the shell-member 13, the said shell-member and the said actuating-sleeve perform as a unit and do not ordinarily shift one with respect to the other.

The turning in a clockwise direction of the body-member 11, carrier 10 and actuating-pin 20 as above described, will cause the said actuating-pin to ride in a helical path bodily outwardly with respect to the structure. This movement of the actuating-pin is, of course, accompanied by a similar movement of the carrier 10 and its contents.

In the manner above described, the material 16 may be projected upwardly through the open upper ends respectively of the body-member 11 and shell-member 13 into convenient position for use.

A reverse or counterclockwise turning movement if now imposed upon the body-member 11, will effect the retirement of the carrier 10 and hence also of the material 16 into a position where the cap 14 may be reapplied to the shell-member 13 and the parts restored to substantially the positions in which they are shown in Fig. 2.

By shaping the shell-member 13 or its equivalent so as to provide an accommodation-channel such as 35 between its inner surface and the

outer surface of the actuating-sleeve 12 or its equivalent, the outer end of the actuating-pin 20 or its equivalent may extend outwardly beyond the outer surface of the said actuating-sleeve to such a degree as to insure its continued coaction with the walls of the inclined actuating-slot 24.

By the construction and arrangement of parts shown in the accompanying drawing, the actuating-sleeve 12 or its equivalent may be made of much thinner material than has been heretofore commercially feasible since the danger of the actuating-pin 20 becoming axially displaced and therefore losing coacting relationship with the walls of the slot 24, is obviated.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable holder for lipsticks and the like comprising: a hollow body-member provided with a substantially-longitudinal guide-slot extending through its side wall; a carrier axially movable within the said body-member; a sleeve-like actuating-member around the exterior of the said body-member and provided with an actuating-slot extending therethrough and inclined relative to the guide-slot in the said body-member; a shell-member around the exterior of the said sleeve-like actuating-member and having a longitudinally-intermediate portion spaced radially outwardly from the outer surface of the said sleeve-like actuating-member to provide an annular accommodation-channel interiorly of the said shell-member and having a length in a direction axially of the said shell-member equal to the axial movement of the said carrier; sleeve-supporting means located adjacent each of the respective opposite ends of the said shell-member to hold the major portion of the inner surface of the said sleeve-like actuating-member spaced from the inner surface of the said accommodation-channel; and a second actuating-member projecting outwardly from the said carrier through the guide-slot in the said body-member and through the actuating-slot in the said sleeve-like actuating-member and into the accommodation-channel within the said shell-member.

2. An adjustable holder for lipsticks and the like comprising: a hollow body-member provided with a substantially-longitudinal guide-slot extending through its side wall; a carrier axially movable within the said body-member; a sleeve-like actuating-member around the exterior of the said body-member and provided with an actuating-slot extending therethrough and inclined relative to the guide-slot in the said body-mem-

ber; a shell-member around the exterior of the said sleeve-like actuating-member and having a longitudinally-intermediate portion spaced radially outwardly from the outer surface of the said sleeve-like actuating-member to provide an annular accommodation-channel interiorly of the said shell-member and having a length in a direction axially of the said shell-member equal to the axial movement of the said carrier; sleeve-supporting means integral with each of the respective opposite ends of the said shell-member and projecting inwardly therefrom to a point beyond the outer surface of the accommodation-channel within the said shell-member to hold the major portion of the inner surface of the said sleeve-like actuating-member spaced from the inner surface of the said accommodation-channel; and a second actuating-member projecting outwardly from the said carrier through the guide-slot in the said body-member and through the actuating-slot in the said sleeve-like actuating-member and into the accommodation-channel within the said shell-member.

3. An adjustable holder for lipsticks and the like comprising: a hollow body-member provided with a substantially-longitudinal guide-slot extending through its side wall; a carrier axially movable within the said body-member; a sleeve-like actuating-member around the exterior of the said body-member and provided with an actuating-slot extending therethrough and inclined relative to the guide-slot in the said body-member; a shell-member extending around the exterior of the said sleeve-like actuating-member and having a longitudinally intermediate portion of substantially-circular form in cross section and spaced radially away from the outer surface of the said sleeve-like actuating-member to provide a substantially-annular accommodation-channel interiorly of the said shell-member and having a length in a direction axially of the said shell-member equal to the axial movement of the said carrier; sleeve-supporting means of cylindrically-contoured form integral with and located adjacent each of the respective opposite ends of the said shell-member and projecting inwardly therefrom beyond the outer surface of the substantially-annular accommodation-channel in the intermediate portion of the said shell-member to frictionally engage and hold the major portion of the inner surface of the said sleeve-like actuating member in spaced relationship away from the inner surface of the said substantially-annular accommodation-channel within the said shell-member; and a second actuating-member projecting outwardly from the said carrier through the guide-slot in the said body-member and through the actuating-slot in the said actuating-member and into the accommodation-channel within the said shell-member to an extent to position its outer end radially outwardly beyond the inner surfaces of the said sleeve-supporting means.

HOWARD F. REICHENBACH.
